UNITED STATES PATENT OFFICE

LOUIS P. WULF, OF LOST NATION, IOWA

AIR-MAIL PICK-UP AND DEPOSIT MECHANISM

Application filed August 23, 1930. Serial No. 477,412.

This invention relates to devices whereby airplanes or other aircraft may pick up mail without alighting and may discharge mail without alighting.

5 One of the objects of the present invention is to provide a construction of this character in which a mail bag suspended by a cable from the aircraft may be guided to an unlatching device which will unlatch the mail bag and permit it to drop and which will simultaneously release another mail bag and engage this second named mail bag with the cable so that the cable may be drawn up to the flying machine with the 10 outgoing mail.

15 A further object is to provide a construction of this character which includes vertical supports, convergent guide members secured to said supports, the guide members 20 at their ends terminating in a device for supporting a mail bag so constructed that as the cable of the aircraft is guided into the throat of the device, the mail bag support will be detached and will be engaged 25 with this cable.

20 A further object is to provide improved means whereby a mail bag may be supported from the cable and detached therefrom when the cable enters the throat of the support.

30 Other objects will appear in the course of the following description.

35 My invention is illustrated in the accompanying drawings, wherein:—

Figure 1 is a diagrammatic perspective view showing my mail catching and discharging apparatus for airplanes constructed in accordance with my invention;

Figure 2 is a longitudinal sectional view 40 of the catching and discharging device for the mail bags;

Figure 3 is a section on the line 3—3 of Fig. 2;

Figure 4 is a fragmentary section on the 45 same plane as Figure 2 but showing the latch tripped;

Figure 5 is a section on the line 5—5 of Figure 2;

Figure 6 is a top plan view partly broken 50 away of the tubular members and the clip;

Figure 7 is a like view to Figure 6 but

showing the clipping member partly withdrawn from the tubular member and the bolt shot;

Figure 8 is a side elevation of the structures shown in Figures 6 and 7;

Figure 9 is an elevation of the means for supporting the incoming mail bag and showing the mail bag in supported position;

Figure 10 is a like view to Figure 9 but showing the mail bag tripped and dropping;

Figure 11 is a vertical sectional view of the mail bag support;

Figure 12 is a section on the line 12—12 of Figure 9;

Figure 13 is a section on the line 13—13 of Figure 10, looking in the direction of the arrows;

Figure 14 is a perspective view of the mail bag catcher, the view being somewhat diagrammatic in character;

Figures 15, 16 and 17 are diagrammatic views showing the position of the parts at the time when the bag is delivered and the other bag received and carried off;

It will be seen from Figures 1 to 14, that the mail bag catching and delivering device on the ground comprises the uprights 10 which at their upper ends are curved toward each other as at 11. These uprights will 80 be approximately forty feet high. Disposed at any desired distance from the uprights 10 there will be uprights 12 held by the guy wires 13 and from these uprights extend the guide wires or elements 14.

The uprights 12 are disposed any desired distance apart and the guide wires 14 converge toward the gap between the portions 11 of the uprights 10. These uprights 10 may also be held in an upright position 90 against strain by guy wires. This construction embodying the guide elements 14 and the tubular parallel elements 16 which are next to be described, constitutes a ground trap for the cable which supports the mail bag or other package.

Mounted at the gap between the portions 11 are the horizontally disposed tubular elements 16 as shown in Figure 6 open at their forward ends, the guide wires 14 leading 100

rectly to the ends of these tubular elements which are beveled so that a cable will be guided into this throat 17 between the tubular elements 16. Detachably mounted with 5 in the elements 16 at the outer ends thereof is a U-shaped clip 18 having its legs inserted within the tubes 16. This clip 18 is held within the tubes 16 by frictional engagement, as for instance, by the plungers 19 urged inward by springs 20, these springs 10 and the plungers being mounted upon housings 21 in turn mounted upon the outer walls of the tube 16, the plungers extending through apertures in the outer walls of the tube and bearing against the legs of the 15 U-shaped clip constituting a coupling member as shown most clearly in Figure 6. The outer end of this clip is provided with an eye 22 with which the mail bag B is engaged by 20 means of the cable 23.

Mounted upon the clip 18 is a bolt 24 shown as extending through a housing 25. A coiled compression spring 26 urges this bolt inward. The inner wall of the tubular 25 member 16 on the side toward this bolt is extended at 27 so that when the clip 18 is in place, this bolt will bear up against this extension 27 of this wall and is prevented from being projected inward and across the 30 bight end of the clip.

When this clip is withdrawn partially from the tubular member 16, however, the bolt 24 will pass the extension 27 and the spring will act to project the bolt directly 35 across the clip. The opposite leg of the clip may be provided with a keeper for this bolt or with an aperture for the bolt.

Disposed in association with the clip is a catapult. The catapult, of course, comprises a supporting frame including longitudinal members 28 channeled to constitute oppositely disposed spaced tracks. Operating within these tracks is a slide 29 supporting a seat 30 for the mail bag B. This slide 40 29 has attached to it the cable 31 which extends to the forward end of the frame formed by the members 28 and is there carried over a pulley 32, thence around a traveling pulley 33 and thence to the frame 34 to 45 which it is attached. Connected to the traveling pulley 33 is a powerful coiled contractile spring or an elastic cable as for instance of rubber or any other retractile member designated generally 35. Where a 50 spring is used either of rubber or metal, the spring is attached at its end remote from the cable 23 to a part of the frame as at 36. It will be obvious now that the contraction of the spring 35 will act to draw the slide 29 to the forward end of the frame but this 55 slide is held in retracted position by a latch 37, thus holding the spring 35 in its expanded condition. A trip cord 38 is attached to the latch 37, extends through suitable guides and is detachably connected to

the cable 23, as for instance, by a member 38a attached to cord 38 and inserted into the member 23a carried by the cable 23. The two members 23a and 38a are sufficiently engaged with each other that they cannot be 60 pulled apart except under considerable tension and will then separate. As soon as the latch is released the spring 35 acts to project the bag B in the general direction of the clip 18 which has been engaged by a 75 cable from the air craft. Preferably the catapult is mounted as illustrated in Fig. 14 at the side of the tubular member 16. I do not wish to be limited to this, however.

For the purpose of delivering a mail bag 80 C from a plane and picking up the bag B, I design that the plane should be provided with the cable 39, the plane being provided with means whereby the cable may be wound up or lowered. This means forms no part 85 of my present invention and, therefore, is not illustrated, it being obvious that any means may be used for this purpose.

The lower end of the cable 39 passes 90 downward through an opening 40 formed in a relatively large head 41 carried on the upper end of a housing generally designated 42. This housing has a neck 43' at its upper end which immediately carries the knob 41. The lower end of the housing is open. The 95 housing is relatively thin in cross section as shown in Figure 12. The cable 39 extends through the aperture 40 and extends to a slide 43 which has sliding fit within the housing 42. This slide is longitudinally 100 slotted at 44 and a pin 45 passes through the housing 42 and through this slot. Thus the slide has limited movement within the housing. Surrounding that portion of the cable 105 39 which extends through the neck 43' and engages the slide is a coiled compression spring 46 which normally urges the slide downward. The lower end of the slide on one side is formed with a vertical notch or slot 47, one wall 48 of this notch being relatively short.

Pivoted upon the opposite wall of this slot, that is, upon the face of the slide 43 is a latch 49. The nose of this latch is adapted to extend across the slot 47. The 110 opposite end of the latch projects out beyond the slide and into the path of movement of the housing 42. Engaged with this latch is a compression spring 50 which is shown as surrounding a rod 51, which is 115 pivotally engaged at 52 with the latch.

This point of pivotal engagement is normally to one side of the center 53 upon which the latch turns. Therefore, this 120 spring will act to hold the latch in the position shown in Figure 9 with its nose extending across the slot 47. A stop 54 of any suitable character may be used to prevent an undue depression of the nose of the latch beyond the holding point of the latch. The 125

mail bag C which is to be delivered from the plane is supported by a short cable 55 and carries at its end a loop or ring 56 through which the nose of the latch is normally disposed. The loop or ring 56 and the member 42 with its latch constitutes in effect a detachable coupling between the mail bag or other package and the supporting cable. When the mail bag C is attached to 5 the carrier on the end of the cable 39, the nose of the latch is disposed through this ring 56. The weight of the mail bag and the weight of the slide, therefore, elongate the contractile spring 46. When the cable 10 is dropped between the wires 14 and the airship moves forward, the cable 39 will engage the clip 18 and will withdraw this clip as shown in Figure 16. As soon as the clip 15 is withdrawn, it will slip on down to the cable 39 as shown in Figure 17 and contact with the housing 42, will force the housing downward, thus causing the housing to release the latch 49, thus retracting the nose of the latch from within the ring 56 and 20 allowing the mail bag C to drop. It will thus be seen that I have provided what is in effect a coupling between the mail bag C and the housing 42, this coupling including a latch as one element and the loop or ring 56 25 as the other element and that this coupling is released as soon as the clip 18 engages the housing 42 and forces the housing downward. The continued movement of the airplane with the cable 39 will at this time pull 30 upon the cable 23 which will pull on the cord 38, releasing the latch 37, thus releasing the catapult which will throw the bag B forward as shown in Fig. 4, under the impulse of the spring 35. Then when the 35 cord 38 becomes taut, the separable connection formed by the parts 23a and 38a as shown in Fig. 4 will be separated and the bag B will be carried off by the airplane. Of course, any suitable winding means may be used 40 within the airplane for winding up the cable 39 which supports the incoming and outgoing mail bags.

The cable 23 is connected to the clip 18 and to the bag B by means of snap hooks or 45 like devices and preferably the bag will be formed with a pocket within which the cable 23 and its snap hooks and a clip 18 may be constantly kept in association with the bag.

It will be seen that I have provided a very 50 simple means whereby a mail bag may be released from a plane or other aircraft and whereby the outgoing mail bag may be picked up by the aircraft and whereby also it is only necessary to be certain that the 55 carrier for the incoming mail bag shall be disposed a sufficient distance below the guide wires 14 that the cable 39 shall pass between said guide wires and be carried down to the throat 17 and then that the housing 42 shall 60 be engaged by the clip 18 to permit the

retraction of the cable 19 and the consequent release of the mail bag.

I claim:—

1. Means for receiving and discharging mail from aircraft including a vertical structure formed to provide a gap, parallel tubular members disposed in said gap and constituting a neck, horizontally disposed guides attached to said tubular members and extending rearwardly therefrom in divergent relation to each other, a U-shaped clip having its legs slidably disposed within said tubular guides, means frictionally retaining said clip in place, a transversely extending normally retracted bolt carried by the clip and a spring urging said bolt to a position across the clip, the clip being attached to an outgoing mail bag and a cable depending from the aircraft and having at its lower end an element larger than the transverse width of the clip whereby as said element is pulled taut, the clip will be engaged and retracted from the neck and the bolt will be projected across the clip to thereby attach the clip to the cable. 70

2. Means for receiving and discharging mail from aircraft including a vertical structure formed to provide a gap, parallel tubular members disposed in said gap and constituting a neck, horizontally disposed guides attached to said tubular members and extending rearward therefrom in divergent relation to each other, a U-shaped clip having its legs slidably disposed within said tubular guides, means frictionally retaining said clip in place, a transversely extending normally retracted bolt carried by the clip, and a spring urging said bolt to a position across the clip, the clip being attached to an outgoing mail bag and a cable depending from the aircraft and having at its lower end an element larger than the transverse width of the clip whereby as said element is pulled taut, the clip will be engaged and retracted from the neck, and the bolt will be projected across the clip to thereby attach the clip to the cable, and a catapult including a seat for the outgoing mail bag, a trigger for holding said catapult in retracted position, and means operatively connecting the trigger with the clip and causing the retraction of the trigger when the clip is pulled out. 75

3. In a mail delivery device for aircraft, a vertical support formed to provide a gap, tubular guides mounted in said gap, a U-shaped clip supported by the tubular guides, guide elements converging to said neck to thereby guide a depending cable from the aircraft into the bight of said clip, means on the depending cable for engaging said clip and withdrawing it from the tubular guides and supporting it from the cable, a catapult including a mail bag seat, and means for holding the catapult in a re- 80

- tracted position, and means for releasing said holding means when the cable has engaged the clip and withdrawn it from the tubular guides.
5. 4. In a mail delivery device for aircraft, a vertical support formed to provide a gap, tubular guides mounted in said gap, a U-shaped clip supported by the tubular guides, guide elements converging to said neck to thereby guide a depending cable from the aircraft into the bight of said clip, means on the depending cable for engaging said clip and withdrawing it from the tubular guides and supporting it from the cable,
- 10 15 20 25 30 35 40 45 50 55 60 65 70 75 80 85 90 95 100 105 110 115 120 125 130
- a catapult associated with the vertical members and including spaced longitudinally extending guides, a slide mounted upon said guides, a mail bag seat carried by the slide, a spring urging said slide to a forward position, a trigger holding the slide in a rearward position, a connection between the mail bag and said clip, and means connected to the flexible connection for releasing said trigger to permit the catapult to project the mail bag.
5. In a mail delivery device for aircraft, a vertical support formed to provide a gap, tubular guides mounted in said gap, a U-shaped clip supported by the tubular guides, guide elements converging to said neck to thereby guide a depending cable from the aircraft into the bight of said clip, means on the depending cable for engaging said clip and withdrawing it from the tubular guides and supporting it from the cable, a catapult associated with the vertical members and including spaced longitudinally extending guides, a slide mounted upon said guides, a mail bag seat carried by the slide, a coiled contractile spring fixed at its rear end, a traveling pulley engaged by said spring, a cable attached at one end of the slide, a fixed pulley at the forward end of the guides through which the cable passes, the cable then passing over the traveling pulley, the extremity of the cable being attached to the forward ends of the guides, a trigger holding the slide retracted, a flexible connection between the mail bag and said clip, and means connected to the flexible connection and the trigger whereby the trigger may be released when the clip is withdrawn from the tubular guides on the vertical members.
- 55 60 65 70 75 80 85 90 95 100 105 110 115 120 125 130
6. A mail bag delivery device comprising upright members formed to provide a gap, a U-shaped element disposed within the gap and having its legs extending rearward, horizontally disposed guides extending converging toward said gap, the aircraft having a depending cable, a housing through which the cable slidably passes, the housing being open at its lower end, a spring surrounding the cable and disposed in the upper end of the housing, means in the upper
- end of the housing against which the spring bears, a slide disposed within the housing, a latching member carried in the lower end of the slide, the slide having a recess across which the latching member normally extends, the latching member being adapted to receive a loop upon a mail bag to be delivered, the tail end of the latching member extending outward beyond the slide and in the path of movement of said housing when the latching member is drawn upward relative to the housing.
7. A mail bag delivery device comprising upright members formed to provide a gap, a U-shaped element disposed within the gap and having its legs extending rearward horizontally disposed guides extending convergently toward said gap, the aircraft having a depending cable, a housing through which the cable slidably passes, the housing being open at its lower end, a spring surrounding the cable and disposed in the upper end of the housing, means in the upper end of the housing against which the spring bears, a slide disposed within the housing, a latching member carried in the lower end of the slide, the slide having a recess across which the latching member normally extends, the latching member being adapted to receive a loop upon a mail bag to be delivered, the tail end of the latching member extending outward beyond the slide and in the path of movement of said housing when the latching member is drawn upward relative to the housing, and a compression spring engaged at its lower end with said slide and at its upper end with the latching member and acting to yieldingly hold the latching member in either its fully projected or fully retracted positions.
8. A mail bag delivery device comprising upright members formed to provide a gap, a U-shaped element disposed in said gap, guides extending convergently toward the gap from a distance, a cable depending from the flying machine, a housing having a neck and an enlarged head through which the cable slidably passes, the housing being open at its lower end, a slide mounted within the housing to which the end of the cable is attached, a coiled compression spring surrounding the cable and disposed between the slide and the enlarged head on the housing, the lower end of the slide being formed with a longitudinally extending recess, a latch pivoted upon the lower end of the slide and having one end normally extending across the recess to thereby receive a loop on the mail bag, the tail end of the latch extending beyond the slide and into the path of movement of the housing when the slide is moved into the housing, and means yieldingly retaining the latch in either its

fully retracted or its fully projected positions.

9. Means for receiving and discharging mail in aircraft including vertical members having inwardly extending upper extremities spaced from each other to form a gap, tubular members mounted at the gap and constituting a neck, guide wires depending approximately horizontally from a distance 10 and converging toward and connected to the ends of the tubular members, a U-shaped clip having its legs disposed within the tubular members, means on the tubular members for frictionally retaining the clip in place, the clip having a cable attached thereto and attached to the outgoing mail bag, a normally retracted bolt spring projected across the clip, means on one of said tubular members for holding said bolt in a retracted 20 position until the clip has been pulled out of the tubular members, a depending cable on the aircraft, and a mail bag tripping and supporting device mounted thereon and including a latch releasing the last named mail bag automatically when the tripping device is engaged with the U-shaped clip.

10. Means for receiving and discharging mail from aircraft including vertical members having inwardly extending upper extremities spaced from each other to form a gap, tubular members mounted at the gap and constituting a neck, guide wires depending approximately horizontally from a distance 30 and converging toward and connected to the ends of the tubular members, a U-shaped clip having its legs disposed within the tubular members, means on the tubular members for frictionally retaining the clip in place, the clip having a cable attached thereto and attached to the outgoing mail bag, a normally retracted bolt spring projected across the clip, means on one of said tubular members for holding said bolt in a retracted 40 position until the clip has been pulled out of the tubular members, a catapult including a sliding mail bag seat for the outgoing mail bag, means acting when the clip is withdrawn from the tubular guides to release said catapult, and means on the aircraft for supporting the mail bag including a cable, a mail bag supporting device on the lower end of the cable having a latch, the mail bag supporting device being wider than the space between the legs of the 50 clip, and means for releasing the incoming mail bag from the mail bag supporting device automatically when the mail bag supporting device has engaged said clip and withdrawn it from the tubular member.

11. Means for receiving and discharging mail from aircraft including a trap comprising guides converging toward each other, there being a gap between the outer ends of said guides, an element removably disposed in said gap and to which the outgoing

mail bag is attached, a cable depending from the aircraft, a mail bag support carried by said cable and including a latch operatively engaging the bag, and means acting when the mail bag support has engaged said element and withdrawn it from said guides to release said bag and release the incoming mail bag.

12. A package transfer mechanism for airplanes including a cable depending from an airplane, means for detachably coupling a package to said cable, a ground trap having converging members into which the cable is guided, the converging members at their proximate ends being formed to provide a throat, a coupling member connected to an outgoing package and removably disposed at said throat, the cable being guided into said coupling member by the throat, the movement of the cable through the throat 75 detaching the coupling member from the throat, and means actuated by the downward movement of the coupling member under the weight of the outgoing package 80 uncoupling the first named package from the cable.

13. Means for receiving and discharging mail from aircraft including a trailing cable from the aircraft and carrying a relatively large body thereon, a ground trap including 95 cable guides converging to a relatively narrow throat and a substantially U-shaped member detachably disposed in said throat and between the legs of which U-shaped member the cable is guided by the throat, the legs being less distance apart than the diameter of said body, said member being connected to an outgoing package, and means for automatically closing the gap between the legs of said U-shaped member 100 when it is displaced by said cable through the throat of the guides whereby said member will be coupled to the cable.

14. Means for receiving and discharging mail from aircraft including a trailing cable from the aircraft and carrying a relatively large body, a ground trap including cable guides converging to a relatively narrow throat, and a substantially U-shaped member detachably disposed in said throat and between the legs of which the cable is guided, the body carried by the cable being larger in diameter than the width of the throat and the U-shaped member, said body constituting a releasable holding means between the cable 110 and an incoming bag, and means causing the release of said holding means after the cable has released the U-shaped member from said guides.

15. Means for receiving and discharging mail from aircraft including a ground trap having cable guides converging to a relatively narrow throat, the throat having parallel portions disposed in a horizontal plane, a horizontally disposed vertically 125

- open U-shaped member having its legs normally disposed in a horizontal plane and supporting the bag with its body disposed adjacent to but in a plane extending across 5 the gap defined by said guides, the outgoing package being operatively connected to said U-shaped member, an aircraft supported cable, a coupling member carried upon the cable and coupling an incoming package thereto, the coupling member having a releasable latch and being larger in diameter 10 than the width across the legs of the U-shaped member, the U-shaped member when engaged by said cable and withdrawn from the guides slipping down the cable under the weight of the incoming package and releasing said latch between the incoming package and the cable.
16. A cable depending from an aircraft 20 and carrying a mail bag supporting element, there being coupling means between the mail bag supporting element and said cable, including a loop and a latching element normally extending through the loop but re- 25 tractible therefrom, a ground trap includ- ing converging guides defining a gap, and means at said gap causing the withdrawal of said latch from the loop when the cable has moved out of the gap.
- 30 17. In a mail delivery device for aircraft, in which the outgoing bag is provided with means whereby it may be engaged and carried away by an airplane, a catapult comprising a slidable seat upon which the bag 35 is initially supported, guides in which said seat moves, a cable attached to the seat passing over a pulley, a fixed support to which one end of the cable is attached, a movable pulley engaged in a bight of the cable be- 40 tween the fixed support and the first-named pulley, a spring engaged with the movable pulley and urging it in a direction to cause the retraction of the cable, and releasable means for holding the seat against move- 45 ment under the action of said spring.
18. In a package transfer apparatus for airplanes having a trailing suspension means depending from the plane and provided with pick-up means for package car- 50 riers, a trap comprising means for guiding said pick-up means, and a package project- ing device coacting with said trap adapted to be set in operation by the picking up of the carrier and comprising a seat, detach- 55 able means for latching the seat from move- ment, longitudinally extending guides upon which the seat is mounted for sliding move- ment, a cable attached to the seat and ex- tending along said guides in a direction 60 away from said latching means, a pulley over which the cable passes, fixed means en- gaging the free end of the cable, a movable pulley engaging the bight of the cable, a contractile spring engaging the movable 65 pulley and urging it in a direction to project

the seat along the guides, and means acting to release said latch upon the picking up of a carrier.

19. Means for receiving and discharging mail from aircraft including a structure 70 formed to provide a gap, horizontally dis- posed guides converging to the gap in said structure, members disposed in said gap and constituting a neck, a U-shaped clip having sliding engagement with said neck members 75 and attached to an outgoing mail bag, a spring projected bolt carried by one of the legs of the clip and projectible across the clip, said bolt being held in a retracted position when the clip is disposed within the neck members, and a cable depending from the aircraft and having a member on its end larger in diameter than the width of the clip whereby when the cable enters said clip and the member engages the clip, the 80 clip will be withdrawn from the neck mem- bers and the bolt automatically projected across the clip behind the cable.

In testimony whereof I hereunto affix my signature.
